AIR INTAKE AND VENTING UNIT FOR HEATERS

Marvin L. Stark, Anchorage, and Frank C. Lewis,
Louisville, Ky., assignors to Peerless Manufacturing
Division, Dover Corporation, Louisville, Ky., a corpo-
ration of Kentucky

Filed July 31, 1963, Ser. No. 76,047

Term of patent 14 years

(Cl. D81—21)

FIG. 1.

FIG. 2.

FIG. 3.

FIG. 1 is a perspective view of an air intake and venting unit for heaters showing our new design.

FIG. 2 is a side elevation of the unit shown in FIG. 1.

FIG. 3 is an end elevation on the same scale as FIG. 2 but showing the back wall of FIG. 1 more clearly.

The undisclosed sides of the screen element are the same in appearance as the side shown and the rear is substantially flat and plain except for a conventional opening.

We claim:

The ornamental design for an air intake and venting unit for heaters, substantially as shown and described.
